UNITED STATES PATENT OFFICE.

ALFRED E. BRUNS, OF BROOKLYN, NEW YORK, ASSIGNOR TO METAL PACKAGE CORPORATION OF NEW YORK, OF BROOKLYN, NEW YORK, A CORPORATION OF NEW YORK.

DESIGN FOR A CONTAINER FOR TOILET POWDERS.

53,984.

Specification for Design.

Patented Nov. 4, 1919.

Application filed June 19, 1917. Serial No. 175,702. Term of patent 14 years.

To all whom it may concern:

Be it known that I, ALFRED E. BRUNS, a citizen of the United States, residing at Brooklyn, New York city, in the county of Kings and State of New York, have invented a new, original, and ornamental Design for a Container for Toilet Powders, of which the following is a specification, reference being had to the accompanying drawings, forming part thereof, in which—

Figure 1 is a top plan view of a container for toilet powders showing my new design.

Fig. 2 is a front elevation of the same.
Fig. 3 is a bottom plan view of the same.
Fig. 4 is a side elevation of the same.

I claim:

The ornamental design for a container for toilet powders, as shown.

ALFRED E. BRUNS.

Witnesses:

E. M. KAYLOR,
R. D. WOODCOCK.
